(57) **CLAIM**

The ornamental design for a desktop riser handle set as shown and described.

DESCRIPTION

FIG. 1 is a perspective view of a desktop riser handle set shown in a fixed position showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view of the desktop riser handle set shown in an adjusting position where the desktop is lowering to a middle position;

FIG. 10 is the other perspective view thereof;

FIG. 11 is a perspective view of the desktop riser handle set shown in a fixed position where the desktop is fixed at the middle position;

FIG. 12 is the other perspective view thereof;

FIG. 13 is a perspective view of the desktop riser handle set shown in a fixed position where the desktop is fixed at the lowered position;

FIG. 14 is the other perspective view thereof;

FIG. 15 is a partial enlarged view of the indicated portion shown in FIG. 1;

FIG. 16 is a partial enlarged view of the indicated portion shown in FIG. 2;

FIG. 17 is a partial enlarged view of the indicated portion shown in FIG. 9; and,

FIG. 18 is a partial enlarged view of the indicated portion shown in FIG. 10.

The broken lines shown represent portions of the desktop riser handle set and environmental subject matter, all of which form no part of the claimed design.

1 Claim, 18 Drawing Sheets
